UNITED STATES PATENT OFFICE.

HENRY V. STEVENS, OF EMPORIA, KANSAS.

DRAFT-REGULATOR.

1,278,516.

Specification of Letters Patent. Patented Sept. 10, 1918.

Application filed June 8, 1918. Serial No. 238,953.

To all whom it may concern:

Be it known that I, HENRY V. STEVENS, a citizen of the United States residing at Emporia, in the county of Emporia and 5 State of Kansas, have invented certain new and useful Improvements in Draft-Regulators, of which the following is a specification.

This invention relates to furnaces, and 10 more especially to draft regulators having an exhaust nozzle with a variable discharge; and the object of the same is to produce an improved form of flexible tip for the discharge nozzle in a locomotive smoke box, 15 and also to produce novel means for operating said tip to enlarge it or reduce it as the case may require.

These objects are carried out by the constructions set forth more fully in the following specification and claims, and shown 20 in the drawings, wherein:—

Figure 1 is a side elevation of a locomotive equipped with this invention,

Fig. 2 is a horizontal section through the 25 smoke box of the boiler showing parts of this invention,

Fig. 3 is an enlarged plan view of the nozzle, and

Fig. 4 a vertical section thereof, while

30 Fig. 5 is a sectional detail on the line 5—5 of Fig. 4.

As to the locomotive, we are concerned only with its cab C and its smoke box B and stack S. The exhaust from the cylinders is 35 usually driven up a nozzle and out the stack with considerable force, due to the contraction of the tip of the nozzle. With certain conditions of the fire, certain pressure of the steam, and on certain grades, it becomes de- 40 sirable to enlarge and at other times to re-duce the size of the tip of this nozzle so as to get the best results from the engine; and it is the object of my invention to con-trol this size from the cab C in order that 45 the engineer shall not have to leave his post.

The upper end of the nozzle is illustrated in section in Fig. 4. Therein it is shown as made up of a two-part ring whose upper and lower parts 1 and 2 are complementary 50 of each other and are channelled on their contiguous faces for the reception of seg-ments 3, 4, 5, and 6 which go to make up the tip itself. These segments are preferably connected with each other at the points 7, 55 8, and 9, but the remaining two ends in-stead of being pivoted to each other are piv-

oted at 10 and 11 to lugs 12 and 13 respec-tively projecting from upper and lower 60 rack bars 14 and 15 which are slidably mounted in a guide 16 formed in an exten-sion 17 at one side of the two parts of the nozzle. The sections or segments have top and bottom grooves 18 loosely engaging 65 ribs 19 in the parts of the nozzle for a pur-pose yet to appear.

Rotatably mounted within the extension 17 is a gear 20 engaging the two rack bars 14 and 15 as best seen in Fig. 5, and this gear is fixed on a shaft 21 which is con-nected by a universal joint 22 with a shaft 70 section 23. The latter in turn is connected by another universal joint 24 with a shaft 25 which leads through the side wall of the smoke box B and carries a beveled gear 26 on its outer end. Said gear meshes with an-75 other beveled gear 27 at the lower end of the shaft 28, and this shaft is connected by gearing 29 with a shaft 30 leading through suitable bearings into the cab C where it has a hand wheel or handle 31 standing within 80 reach of the engineer. Suitable means are here provided to indicate on the wheel or adjacent to the wheel how the parts within the smoke box are set. I will say at this point that the gearing and universal joints 85 shown herein are those adapted to a stand-ard make of locomotive, but may have to be altered to adapt them to other makes. The point is that the long shaft 30 shall be connected by some means with the shaft 21 90 which carries the gear 20, so that when the hand wheel 31 is turned the gear 20 will be turned and the rack bars adjusted sim-95 ultaneously and oppositely.

When now it is desired to reduce the size 95 of the tip of the nozzle, the hand wheel 31 is turned in a proper direction to cause the rack bars to slide toward each other, the uppermost 14 moving to the left in Fig. 5, and the lowermost 15 to the right. Through 100 their connection with the sectors or segments 4 and 6, this motion draws the sectors toward each other as the looseness of the grooves 18 on the ribs 19 permits, and in fact all of the four sectors are drawn inward and the mouth of the nozzle is reduced to per-105 haps five inches. Reverse movement of the hand wheel 31 causes a reverse movement of the gear 20 and the spreading apart of the contiguous ends of the segments 4 and 6. 110 This is communicated through the pivots 7 and 9 to the other segments 3 and 5, and all

of the sections are pushed outward as far as the looseness of the grooves 18 on the ribs 19 will permit. Thereby the mouth of the nozzle may be increased in size, possibly to 5 five and one-half inches or even more. The parts should be kept well oiled, and on occasions should be cleaned or cleansed to remove the gum and grease which accumulates invariably at the tip of the nozzle.

10 The foregoing description and the drawings have reference to what may be considered the preferred, or approved, form of my invention. It is to be understood that I may make such changes in construction and 15 arrangement and combination of parts, materials, dimensions, et cetera, as may prove expedient and fall within the scope of the appended claims.

Having thus fully described my invention, 20 what I claim as new and desire to secure by Letters Patent, is:—

1. In a draft regulator, a nozzle tip made in superposed complementary parts channeled in their meeting faces, a ring made up 25 of segments lying within said channels, pivotal connections between the segments at all points but one, and lugs projecting from this point radially outward; combined with complementary rack bars movable in guides, 30 connections between each rack bar and one of said lugs, and means between the rack bars for moving them simultaneously and oppositely.

2. In a draft regulator, a nozzle tip made 35 in superposed complementary parts channeled in their meeting faces and provided with ribs in their channels, a ring made up of segments lying within said channels and having grooves at top and bottom loosely 40 engaging said ribs, pivotal connections between the segments at all points but one, and lugs projecting from this point radially outward; combined with extensions on said parts having complementary guides, rack 45 bars movable in said guides, connections between each rack bar and one of said lugs, and means between the rack bars for moving them simultaneously and oppositely.

3. In a draft regulator, a nozzle tip made in superposed complementary parts channeled in their meeting faces and provided with ribs in their channels, a ring made up 50 of segments lying within said channels and having grooves at top and bottom loosely engaging said ribs, pivotal connections between the segments at all points but one, and lugs projecting from this point radially outward; combined with extensions on said parts having complementary guides, rack 55 bars movable in said guides, connections between each rack bar and one of said lugs, a shaft journaled in the extensions, a gear fast thereon and engaging said rack bars simultaneously, and means for turning the shaft from a distant point to adjust the rack bars 60 simultaneously and oppositely, for the purpose set forth.

4. In a draft regulator, means for adjusting the size of a nozzle tip consisting of a ring made up of a plurality of sections 70 pivotally connected with each other, the tip being channeled for the loose reception of said ring, two of its sections having outstanding lugs, two bars having rack teeth facing each other and respectively pivoted 75 to said lugs, and a gear between said bars and simultaneously engaging said teeth, for the purpose set forth.

5. An adjustable nozzle tip comprising two parts channeled on their meeting faces 80 to complement each other and having extensions also channeled to complement each other, a ring made up of a plurality of sections all pivotally connected to each other except at one point, elements projecting 85 from the sections at said point into the channel of said extensions, and manually adjustable members within said channel movable oppositely for adjusting said elements, for the purpose set forth.

In testimony whereof I affix my signature in presence of two witnesses.

HENRY V. STEVENS.
